ELECTRONIC DEVICE CIRCUIT

Gordon B. Jacobs, Carthage, N. Y., and Oliver I. Steigerwalt, Chicago, Ill., assignors to the United States of America as represented by the Secretary of War

Application March 4, 1946, Serial No. 651,935

3 Claims. (Cl. 315—106)

1

This invention relates to electronic device circuits, and, more particularly, to a circuit arrangement for regulating or controlling an operating characteristic of a magnetron.

It has been observed that the efficiency of operation of a magnetron is affected by variations or change in the temperature of the cathode of the magnetron during the operation of such a device. It is generally intended or desired that the cathode operate at a preassigned normal operating temperature. It has been found that variation from this temperature occurs when, during operation of the magnetron, the cathode is subject to back heating as a result of electron bombardment.

It is an object of this invention to stabilize the temperature of a magnetron cathode during the operation of such a device.

A feature of the invention comprises magnetron cathode-temperature regulating means for stabilizing the cathode temperature in response to changes or variations in the cathode temperature during operation of the magnetron.

In accordance with the invention, a circuit arrangement is associated with a magnetron filament or cathode to regulate the temperature thereof during operation of the device. The regulating circuit is incorporated in the cathode heating power supply, and is responsive to resistance changes of the cathode with temperature change thereof, to vary the heating power input to the magnetron cathode.

A more complete understanding of the invention, of its other objects and features together with their attendant advantages, will be derived from the detailed description that follows, taken in conjunction with the showings of the appended drawing, wherein:

Fig. 1 shows a circuit arrangement embodying the invention; and

Fig. 2 shows schematically the mechanical coupling between the control motor and adjustable components included in the circuit arrangement of Fig. 1.

There is shown a magnetron 10 comprising a filamentary cathode 12 and anode 14. The filament is heated by alternating current, through a filament transformer 16. The heating power supply for the filament may comprise a 3-phase alternating current supply, transformed through a Scott-connected type transformer 18 to 2-phase alternating current, one phase of which is applied through transformer winding 20 to one field winding 22 of the control or servo motor 24, the other phase of which is applied through trans-

2

former winding 26 to the primary winding of the transformer 16. A variable autotransformer 28 is connected across the winding 26 to enable variation, under control of motor 24, of the voltage furnished to the filament transformer. The primary winding of a voltage transformer 30 is connected in parallel with the autotransformer, and a current transformer 32 is connected in series with the primary winding of transformer 16. The transformers 30, 32, are so constructed that their secondary voltages are approximately equal when the reflected filament resistance, as given by the ratio of the voltage across and the current flow through the filament transformer primary, is normal indicating the desired or proper filament temperature. A manually adjustable compensating potentiometer 34 is connected across the secondary winding of transformer 32, and an automatically regulated potentiometer 36, 20 adjustable under control of the motor 24, is connected across the secondary winding of the transformer 30. The potentiometers are connected through the primary winding of an input transformer 38 to an amplifier 40. An automatic gain 25 potentiometer 42 may be connected across the secondary winding of transformer 38, being adjustable under control of the motor 24. The secondary winding of the amplifier output transformer 44 is connected to the second field winding 46 of the control motor 24. The mechanical coupling from the motor 24 to the autotransformer and to the potentiometers 36, 42 is indicated by the dotted lines in Fig. 1. Fig. 2 indicates, schematically, a suitable arrangement in which 35 the autotransformer and potentiometers may be driven through a suitable friction clutch 48, and cam-cam stop 50 for limiting extreme adjustments of the transformer and potentiometers.

The operation of the circuit arrangement of Fig. 1 will now be described.

The cathode of a magnetron is generally designed to operate most efficiently at an approximately constant high temperature. During the operation of the magnetron, however, the temperature of the cathode may increase beyond the normal or desired value because of back heating of the cathode as a result of electron bombardment. Because of the radio frequency potential between the cathode and anode, not all of the electrons emitted by the cathode reach the anode, but some of them are directed back to the cathode, to change the latter's temperature in proportion to the number and the intensity of such returned electrons.

For the normal temperature condition of the

cathode, the autotransformer 28 and the manually adjustable potentiometer 34 will have an initial or normal setting, and the network comprising the transformers 30, 32 and potentiometers 34, 36 will be in balance. Should the temperature of the cathode change, the change in the reflected resistance of the cathode changes the voltage appearing across the primary of transformer 30 and the current flowing in the primary of transformer 32 and unbalances the above-mentioned network. A fraction of each of the voltages across the secondaries of transformers 30, 32 is taken from the potentiometers 34, 36 and the difference between these fractions is applied to the amplifier through transformer 38. The difference signal appears at the amplifier input control grid plus or minus 90 degrees out of phase with the voltage applied to the field winding 22 of the motor 24. The input to the amplifier is amplified and applied to the field winding 46 of motor 24, the latter turning in a direction determined by the phase of the amplifier output, to change the adjustment of the autotransformer, and, hence, the cathode heating power supplied to transformer 16. When the cathode temperature again becomes normal, the voltages across transformers 30, 32 will again be of proportions establishing balance in the network including potentiometers 34, 36. Under the latter condition, there will be absence of signal input to the amplifier, field winding 46 will no longer be energized, and there will be no further motion of the motor. The gain control potentiometer 42 is varied or adjusted by the motor 24, simultaneously with adjustment of the autotransformer, to maintain constant sensitivity of the arrangement to temperature changes as the absolute values of voltage and current vary with the adjustment of the variable autotransformer's setting.

A specific magnetron circuit to which the invention is applicable may include a magnetron in which only a portion of the filamentary cathode is subject to back heating and, consequently, variation in temperature from this cause. In such a situation, the total resistance of the filament at any time is the sum of the resistance of the back heated portion and of the remaining portion of the filament. When the variable autotransformer has been adjusted as outlined hereinabove, the temperature of the non-back heated filament portion will be changed from its normal temperature, and the total resistance of the filament, therefore, may not be that for proper operation of the back heated portion of the filament. To compensate for this, the potentiometer 36, under control of the motor 24, is adjusted simultaneously with the adjustments of the autotransformer and of the potentiometer 42, to change the proportion of the current and voltage signal input to the amplifier for balance to account for such change in resistance.

Although, in this description, reference has been made to a filamentary type cathode for the magnetron, obviously the arrangement is readily applicable to a magnetron in which the cathode is of the indirectly heated type.

Although the invention has been disclosed with reference to a specific embodiment, it will be understood that it is not limited thereto, but is of a scope evidenced by the prior art and the appended claims.

What is claimed is:

1. A circuit arrangement for maintaining substantially constant temperature in a magnetron

filamentary cathode, that comprises a source of polyphase alternating current, means for heating the cathode from said source, said means comprising an adjustable autotransformer for furnishing one phase of said alternating current to said cathode, and a multiwinding filament transformer between said autotransformer and said cathode, a multiwinding voltage transformer connected in parallel with the primary winding of said filament transformer, a multiwinding current transformer connected in series with the primary winding of said filament transformer, a compensating potentiometer connected across one winding of said voltage transformer, a second potentiometer connected across one winding of said current transformer and manually adjustable for presetting the temperature of said cathode, an amplifier for amplifying any difference voltage developed across said potentiometers, a multiwinding transformer coupling said potentiometers to the input of said amplifier, a gain adjusting potentiometer across the input to said amplifier, an induction motor having a pair of field windings, one of said windings being energized with one phase of said polyphase alternating current, means for connecting the output of said amplifier to the second of said motor field windings to energize said second winding for movement of said motor upon development of a difference voltage between said compensating and manually adjustable potentiometers on change in temperature of said cathode, and means connecting said motor and said autotransformer, compensating potentiometer and gain adjusting potentiometer for adjustment of said autotransformer and potentiometers in accordance with movement of said motor.

2. A circuit arrangement for maintaining substantially constant temperature in a filament comprising a source of alternating current, means for heating the filament from said source, said means comprising an adjustable autotransformer, a filament transformer, a voltage transformer, a current transformer connected in series with the primary winding of said filament transformer, said series circuit being connected in parallel with said voltage transformer to the output of said autotransformer, a compensating potentiometer connected across one winding of said voltage transformer, a second potentiometer connected across one winding of said current transformer and manually adjustable for presetting the temperature of said filament, an amplifier, a transformer coupling said potentiometers to the input of said amplifier, a gain adjusting potentiometer across the input to said amplifier, a motor, means for connecting the output of said amplifier to said motor for movement of said motor upon development of a difference voltage between said compensating and manually adjustable potentiometers on change in temperature of said filament, and means connecting said motor to the adjusting means of said autotransformer, compensating potentiometer and gain adjusting potentiometer for adjustment of said autotransformer and potentiometers in accordance with movement of said motor.

3. A temperature regulator for controlling the heating of an electron discharge device comprising a source of alternating current, means for heating comprising an adjustable autotransformer and a filament transformer, means for producing a signal responsive to a change in temperature comprising a first transformer in parallel with said autotransformer, a series circuit comprising said filament transformer and a sec-

ond transformer, said series circuit connected in parallel with said first transformer, a potentiometer connected across the secondary of said first transformer, a potentiometer connected across the secondary of said second transformer whereby a change in a reflected resistance of said filament transformer due to the change in temperature will cause an unequal change in the potentials across said potentiometers, means for operatively applying said potential difference to regulate the temperature, said means comprising an amplifier, a transformer means for applying said potential to said ampli-

fier, means for connecting said amplifier output to a motor to adjust said autotransformer.
